UNITED STATES PATENT OFFICE.

HENRY F. SCHMIDT, OF SWARTHMORE, PENNSYLVANIA, ASSIGNOR TO WESTINGHOUSE ELECTRIC & MANUFACTURING COMPANY, A CORPORATION OF PENNSYLVANIA.

CONDENSER.

Application filed February 20, 1920, Serial No. 360,188. Renewed April 20, 1921. Serial No. 462,993.

To all whom it may concern:

Be it known that I, HENRY F. SCHMIDT, a citizen of the United States, and a resident of Swarthmore, in the county of Delaware and State of Pennsylvania, have made a new and useful Invention in Condensers, of which the following is a specification.

My invention relates to condensing apparatus and particularly to condensers of the surface type and it has for its object to provide a compact form of apparatus of the character specified and one wherein the fluid to be condensed, passes through a short path of cross-section proportional to the volume thereof, the condensable fluid and the non-condensable residue being effectively separated and the condensate being operative to cool the incoming condensable fluid.

There are certain principles of condenser construction that have been found to produce the best obtainable results, that is, condensers having a short flow through the cooling tube nests offer the least resistance to the passage of fluid to be condensed, and therefore the difference in pressure between the point of complete condensation and the fluid inlet to the condenser is held to a minimum, and the best distribution of cooling surface is obtained in condensers having diminishing or converging condensing area from the inlet toward the point of complete condensation within the condenser. I have further found that the ejector for the non-condensable fluids operates with improved efficiency when the density of the fluid is increased by cooling prior to its passage to the ejector, and that the general efficiency of the condenser is increased by subjecting the condensate as it rains from the tube nest to direct contact with the incoming steam.

In the accompanying drawing Fig. 1 is a diagrammatic transverse section through a condenser embodying the features of my invention, and Fig. 2 is a diagrammatic longitudinal section thereof.

Referring to the drawing, the condenser illustrated includes a shell comprising a semi-circular bottom portion 2 and a pair of upwardly converging upper walls 3, which meet at a joint directly over the center of the semi-circular wall 2 and between two fluid inlets 4, disposed on opposite sides of the condenser shell. The fluid inlets 4 are each provided with an expansion joint 5,

which is adapted to connect directly with an exhaust passage 6 of the turbine or apparatus served by the condenser. It will be noted that the upwardly converging upper walls of the condenser shell extend above the inlet passages 4 and into the space between the expansion joints 5, thereby advantageously utilizing the space available between these joints for condenser apparatus.

As shown, the shell is provided with a nest of cooling tubes of the double-pass type. These tubes extend longitudinally of the shell and are divided into an upper group A receiving the first pass of water and a lower group B receiving the second pass of water. The arrangement of the headers for circulating the water through the tubes is well known in the art and need not be described in detail. As shown in Fig. 2, water box 12 is divided by means of partition 13 into inlet and outlet compartments 14 and 15, having inlet and outlet connections 16 and 17, respectively, and water box 18 is of the usual return flow structure. The arrangement is such in this case that the cold water entering the water box 12 first passes through the upper group A and then through the lower group B and out of the condenser.

The cooling tubes are arranged to fill the angular upper portion of the condenser and extend downwardly in the form of a semi-circle into the space formed by the semi-circular shell 2. The centers of curvature of the lower portion of the tube nest and of the condenser shell are disposed eccentrically with respect to one another and therefore the steam space 7 between the condenser shell and the tube nest diminishes in sectional area and capacity from the inlet 4 to the lower part of the shell. The steam spaces are, however, of sufficient capacity to supply the nest with substantially uniform quantities of steam throughout the exposed area of the nest.

The non-condensable fluid offtake 8 is located at the point of convergence of the upper walls of the condenser and therefore steam entering the inlets 4 flows in radial directions from the exposed surface of the tube nest toward the air offtake 8, first encountering the warmer tubes in the group B and finally encountering the cooler tubes in

the group A. It will be noted that the fluid or steam encounters a diminishing number of tubes as it progresses toward the air off-take, the cooling area being substantially proportional to the quantity of steam passing the tubes. This arrangement has the advantage that only the actual number of tubes required to accomplish complete condensation are disposed in the path of the steam and therefore the obstruction to steam flow is reduced to a minimum.

Inasmuch as the air is drawn off at the top of the nest, it does not contact with the hot condensate raining through the nest, or the heated fluid entering the condenser through the inlet. In order to additionally cool the non-condensable fluids in the condenser passing to the air off-take, a series of interleaved baffles 9 may be inserted between the uppermost tubes, so that the air or other non-condensable fluids must traverse a tortuous path past a series of cold tubes receiving the first pass of cooling water. The temperature of the air is materially reduced below that of the fluids in the lower part of the condenser and its density is therefore increased. For this reason, the ejector serving the condenser operates more efficiently with the result that an operating economy is obtained.

The hot well 10 of the condenser is located at the bottom of the shell, directly beneath the nest of tubes. Condensate raining from the tube nest passes through the hot incoming steam in the steam space 7 and absorbs the heat thereof with the result that steam is condensed by the falling condensate and the temperature of the condensate is raised to approximately the temperature of the incoming steam. This action results in a still further economy where the condensate is used for feed water purpose.

While I have shown my invention in but one form, it will be obvious to those skilled in the art that it is not so limited but is susceptible of various other changes and modifications without departing from the spirit thereof and I desire, therefore, that only such limitations shall be placed thereon as are imposed by the prior art or as are specifically set forth in the appended claims.

What I claim is:

1. A condenser comprising a shell and a nest of tubes within the shell, the said shell being provided with a pair of spaced inlet passages adapted to admit fluid to opposite sides of the nest of tubes and a non-condensable fluid off-take between the said inlet passages and above the nest of tubes.
2. A condenser comprising a shell and a nest of tubes within the shell, the said shell being provided with a pair of spaced inlet passages adapted to admit fluid to opposite sides of the nest of tubes, a non-condensable fluid off-take between the said inlet passages

and above the nest of tubes, and a condensate discharge port in the bottom of the shell beneath the tubes.

3. A condenser comprising a shell having its upper walls converging upward and having inlet passages adapted to admit fluid to opposite sides of the shell, a nest of tubes within the shell extending into the converging upper portion and below the intake passages, and a non-condensable fluid off-take in the upper portion above the nest of tubes.

4. A condenser comprising a shell having its upper walls converging upward and having inlet passages adapted to admit fluid to opposite sides of the shell, a nest of tubes within the shell extending into the converging upper portion and below the intake passages, a non-condensable fluid off-take in the upper portion above the nest of tubes, and interleaved baffles adjacent the fluid off-take adapted to lengthen the path of flow of the fluids from the side inlet passages to the fluid off-take.

5. A condenser comprising a shell having its upper walls converging upward and having an inlet passage below the converging walls, and air off-take adjacent the point of convergence of the upper walls, and a nest of tubes in the converging portion of the shell disposed between the said fluid inlet and the said air off-take.

6. A condenser comprising a shell having its upper walls converging upward and having an inlet passage below the converging walls, an air off-take adjacent the point of convergence of the upper walls, a nest of tubes in the converging portion of the shell disposed between the said fluid inlet and the said air off-take, and interleaved baffles adjacent the air off-take arranged to lengthen the course of the flow of fluid from the inlet passage to the fluid off-take.

7. A condenser comprising a shell having a semi-circular bottom portion and an upper section provided with a pair of fluid inlets, a nest of tubes within the shell disposed between the said fluid inlets and forming steam passages between the nest and the shell, communicating with the inlets and diminishing in capacity from the inlets toward the bottom of the shell, and a non-condensable fluid off-take located in the upper portion of the shell and between the said inlets.

8. A condenser comprising a shell having a semi-circular bottom wall and upwardly converging upper walls, and provided with a pair of fluid inlets disposed at opposite sides of the shell, a nest of tubes within the shell having its lower portion formed in a semi-circular group spaced from the lower wall of the shell and forming a fluid passage between the lower portion of the nest and the lower wall of the shell, communicating with said inlets, the upper portion of the said nest being shaped to conform with the

converging upper wall of the shell, and a non-condensable fluid off-take in the upper part of the shell above the nest of tubes.

9. A condenser comprising a shell having a semi-circular bottom portion and a converging upper portion, steam intakes below the converging portions, a non-condensable fluid off-take adjacent the point of convergence of the upper walls, first- and second-pass cooling tubes in the condenser, said second-pass tubes being arcuately disposed eccentrically to the bottom portion whereby radial flow of fluids is assured.

10. A condenser comprising a shell and a nest of tubes within the shell, means for admitting a fluid to be condensed to a side of the tube nest and a non-condensable fluid offtake at the upper portion of the tube nest.

11. A condenser comprising a shell having inlet passages terminating at the opposite sides of the shell, a nest of tubes within the shell having a portion of the tubes extending upwardly from the ends of said inlet passages, and a non-condensable fluid offtake at the upper portion of the tube nest.

12. A condenser comprising a shell and a nest of tubes within the shell, a non-condensable fluid offtake located at the upper portion and centrally of the tube nest, a pair of inlet passages within the shell adapted to direct fluid downwardly to the opposite sides of the tube nest and so disposed that the direction of travel of fluid through the tube nest is essentially upward toward the non-condensable gas offtake.

13. A condenser comprising a shell and a nest of tubes within the shell, the upper portion of the tube nest converging toward the top of the condenser, inlet passages adapted to admit fluid to the tube nest from opposite sides and below the converging portion of the tube nest and a non-condensable fluid offtake at the upper portion of the tube nest.

14. A condenser comprising a shell having a semicircular bottom portion, a nest of cooling tubes within the shell having its upper portion in the form of an upwardly extending group of tubes and its lower portion in the form of a semicircular group of tubes spaced from and eccentrically disposed with relation to the bottom of the shell, inlet passages adapted to direct fluid to the opposite sides of the tube nest and into the space between the lower portion of the tube nest and the bottom of the shell, and a non-condensable fluid offtake in the upper part of the shell at the apex of the converging portion of the tube nest.

15. A condenser comprising a shell having a semicircular bottom portion, a nest of tubes within the shell having its lower portion in the form of a semicircular group spaced from and eccentrically disposed with relation to the bottom of the shell, inlet passages adapted to direct fluid to the opposite sides of the tube nest and into the space between the lower portion of the tube nest and the bottom of the shell, and a non-condensable fluid offtake at the upper portion of the shell.

16. A condenser comprising a shell having a semicircular bottom portion, a nest of tubes within the shell having its lower portion in the form of a semicircular group spaced from the bottom of the shell, inlet passages adapted to direct fluid to the opposite sides of the tube nest and into the space between the lower portion of the tube nest and the bottom of the shell, and a non-condensable fluid offtake at the upper portion of the shell.

In testimony whereof, I have hereunto subscribed my name this 17th day of February, 1920.

HENRY F. SCHMIDT.
